UNITED STATES PATENT OFFICE.

WALTER H. JANKE AND JOSEPH A. HALE, OF OMAHA, NEBRASKA.

RATCHET ACTUATING AND RELEASE MECHANISM.

1,198,132.

Specification of Letters Patent. Patented Sept. 12, 1916.

Application filed December 21, 1915. Serial No. 68,075.

To all whom it may concern:

Be it known that we, WALTER H. JANKE and JOSEPH A. HALE, citizens of the United States, residing at Omaha, in the county of Douglas and State of Nebraska, have invented certain new and useful Improvements in Ratchet Actuating and Release Mechanism, of which the following is a specification.

- 10 This invention pertains to ratchet-actuating and release mechanism intended more particularly for use in connection with railway car brakes, though capable of use in other relations also.
- 15 The structure is designed to meet all United States safety appliance requirements for railway and like service, and at the same time obviate certain objections to and offer various advantages over existing types 20 of hand-wheel or lever ratchet-actuating mechanisms.

The new construction will first be described in connection with the accompanying drawings, and the mode of operation and 25 special advantages will then be pointed out and claimed.

In the drawings: Figure 1 is a front or face elevation of the actuating mechanism, the hand-levers being broken away in this 30 and other figures to bring the drawings within the available space on the sheet; Fig. 2 is a vertical section in the plane of the axis of the shaft or arbor of the winding-drum, said shaft and portions of the actuating 35 levers being however shown in elevation; Fig. 3 is a front or face elevation showing the parts in releasing adjustment or position; Fig. 4 is a front elevation of the main supporting member or body; Fig. 5 is 40 a sectional view thereof on the line 2--2 of Fig. 4; Fig. 6 is a perspective view of the pawl-carrying hand lever through which rotary motion is imparted to the drum on which is wound the brake or other chain or 45 cable; Fig. 7 is a perspective view of the combined winding drum and ratchet-wheel; Fig. 8 is a perspective view of the actuating-pawl; Fig. 9 is a perspective view of the retaining and releasing pawl; and Fig. 10 is 50 a view illustrating the manner of attaching the brake or other chain to the drum.

The drawings illustrate an embodiment of

the invention suitable for use on a vestibuled railway passenger car, where it is desirable that the mechanism be capable of 55 operation from within or without the car, at will. In these drawings, 1 indicates one of the upright members of the vestibule end, to opposite faces of which are secured suitable sheathings 2 and 3, here shown of thicknesses to indicate metal, though of course any usual end or wall construction may be used. The sheathings will of course extend from one to another upright, and be 60 suitably secured thereto as usual.

Secured to one face of the wall is a main supporting member 4, which will usually be formed of cast metal and of the general construction illustrated in Figs. 1 to 5, while to the opposite face of such wall is secured 70 a second supporting member or casting 5. These members 4 and 5 are each provided with a circular opening, which openings are in axial alinement to receive and support a cylindrical shaft or arbor 6, the ends of 75 which are made polygonal to receive correspondingly socketed hubs of hand-levers 7 and 8, which are held in place by nuts 9 applied to the threaded extremities of the shaft or arbor. These levers 7 and 8 may 80 take any desired form, as for instance that of hand-wheels.

It will be observed upon referring to Fig. 2 that the shaft or arbor 6 is not reduced to 85 form journals to rest and turn in the bearings of the supports 4 and 5, but is left of full diameter throughout the cylindrical portion, thereby securing the maximum strength and lessening the work of construction, since the stock material may be cut to 90 the required length, and prepared for use by merely squaring and threading the ends of the pieces so cut off. To prevent longitudinal play of the shaft or arbor 6, there is formed upon the hub of lever 7 a peripheral 95 flange 10, which enters between the outer face of shaft-supporting arm or bracket 11 of casting 4 and the inner face of a lug or projection 12 formed upon said bracket or its stiffening web, as seen in Figs. 1 to 5. This 100 construction is simple and efficient, and prevents longitudinal play of the shaft or arbor while permitting it to be made of whatever length required by the thickness of the

wall or partition through which the armor passes. Loosely encircling shaft or arbor 6 is a drum 13 having at one end a ratchet-wheel 14, and at or near its other end a spiral hub or boss 15 of volute form, grooved on its peripheral surface to form a seat for a chain or cable 16. This drum 13 is made of suitable length to enable a sufficient length of the chain or cable to wind about it, the hub 10 or boss 15 serving both as a place of attachment, and, by reason of its spiral or screw-like formation, to give direction to the chain at the commencement of its winding upon the drum. As seen in Fig. 10, the hub or 15 boss 15 is formed with a spur or lug 17 on its straight or tangential face, and with a bolt-hole in line with the inner side or-face of said lug, a suitable recess being made for the head of the bolt 18, as shown. Under 20 this construction, a link 19 of the chain will find a flat or plane bearing on the tangential face of the hub 15. The bolt 18 receives support from the spur or lug 17 to prevent its being bent over by the pull of the chain, 25 and the link 19 is held by the bolt 18 and the spur 17 against lateral movement or deflection, thus causing the next link of the chain to lie in and follow the groove 20 in the peripheral face of the hub 15, which 30 directs the chain properly to the cylindrical portion of the drum 13. A tap-bolt may of course be employed instead of the bolt and nut shown in the drawing, in which case the bolt-hole will be suitably threaded to 35 receive the same.

The outer face of the ratchet-wheel 14 is recessed to receive or to overhang the upper end of the supporting arm or bracket 11 of the main supporting-member 4, against 40 which the proximate end of the drum or the web of the ratchet-wheel formed thereon finds a bearing. The rear or inner face of said ratchet-wheel bears against a face 21 of the main supporting-member 4 intermediate 45 at the inner face of bracket 11 and the base or securing-plate of said member 4. In this way, longitudinal play of the drum 13 is prevented, though the parts are fitted sufficiently loosely to permit free turning of 50 the drum. Sufficient opening is allowed between the bracket 11 and the bearing face 21 to permit the introduction of the ratchet-wheel 14 between them, prior to placing the shaft or arbor 6 in position, the drum being 55 first properly aligned and the shaft or arbor thereafter passed through its bearings and through the drum, and serving to support and retain the latter in its working position.

22 indicates an actuating-pawl pivotally 60 mounted upon a lateral extension 23 of the lever 7, a suitably shouldered pin or bolt 24 serving as a pivot for said pawl. This pawl 22 is of a width or thickness approximately half that of the ratchet-wheel 14,

and falls by gravity into engagement with 65 the periphery of said ratchet, a lug or stop 23 on the lever 7 limiting the play of said pawl, and maintaining it always in operative relation to the ratchet-wheel. Upon swinging said lever 7 in a right-hand direction as the parts are viewed in Fig. 1, the tooth or hook of actuating-pawl 22 is caused to ride over the rear oblique faces of the ratchet teeth, and upon reversing the movement of said lever, engages with one of said 75 teeth and rotates the ratchet-wheel 14 and the drum 13 by which it is carried, in the direction indicated by arrow in Fig. 1, thereby causing the chain 16 to wind upon and about said drum. The free end of actuating-pawl 22 is beveled as shown in Figs. 1, 3 and 8, for a purpose presently pointed out.

To hold the drum 13 against backward rotation, there is provided a second or retaining-pawl 25 carried by a suitably shouldered pivot-bolt 26 passing through the intermediate plate 27 on support 4, the front of which plate constitutes the bearing face 21 above noted. This retaining-pawl 25 is, like the actuating-pawl 22, of a width or thickness approximately one-half that of the ratchet-wheel 14, and the tooth or hook at its free end rests upon the ratchet teeth, and falls by gravity into engagement with 95 their radial or locking faces as the ratchet-wheel is turned in a backward or winding direction. The free end of said pawl 25 is formed with a lateral stud or projection 28—29, as shown in Figs. 1, 3 and 9, the 100 portion 28 projecting only to the extent of the thickness or width of actuating-pawl 22, while the portion 29 projects farther and stands in the path of a cam 30 formed upon the lever 7 near its hub or point of 105 attachment to the shaft or arbor 6.

If now, when the parts constructed as above described and as shown in the drawing, lever 7 or lever 8, either or both, be oscillated about the axis of arbor 6 but not 110 moved to carry lever 7 in clockwise direction materially beyond the vertical position indicated in Fig. 1, the drum 13 may be rotated and the chain or cable 16 wound thereon to any extent desired, and reverse 115 rotation and unwinding of the chain or cable 16 will be prevented by the holding or retaining action of pawl 25. When, however, it is desired speedily to release the ratchet 14 and permit unwinding of the 120 chain 16, it is necessary only to swing the lever 7 clockwise until the beveled end of pawl 22 engages and rides upward upon the portion 28 of stud 28—29, thereby withdrawing the tooth or hook of pawl 22 from 125 engagement with the teeth of ratchet 14, immediately after which the outer or bearing face of cam 30 of lever 7 rides be-

neath portion 29 of the lug 28—29, and in turn lifts the tooth or hook of pawl 25 out of engagement with the teeth of the ratchet 14, the pawl 22 being carried higher through such lifting of pawl 25. This sequence in the lifting of the pawls is important, for the reason that the actuating-pawl carried by the hand-lever is thus fully disengaged and maintained clear of the ratchet-wheel 10 before pawl 25 releases said wheel, and cannot again go into engagement with the ratchet-wheel until after the retaining-pawl 25 has reengaged it. Hence impact of the ratchet-wheel against the actuating-pawl 15 and consequent transmission of shock to the operator through the hand-lever 7, in the event of premature release or backward movement of said lever, is precluded. It is of course immaterial which of the levers 7 or 8 is utilized to operate the device. It is also obvious that said levers may each of them be placed at any desired angular adjustment with reference to arbor or shaft 6.

When the chain or cable 16 is partially wound and a load is brought upon the drum 13, the pressure exerted by a tooth of the ratchet 14 upon the tooth or hook of the retaining-pawl 25 will be sufficient to prevent the lifting or disengagement of said pawl except through the application of a considerable force. Hence there is no danger ordinarily of the pawl being lifted by cam 30 through the mere falling of the lever 7 to the right, and consequent engagement 35 of said cam with the stud 28—29. The throw of the lever 7 in the direction indicated by the arrow in Fig. 1, is limited by a stop 31 on the bracket 11, and throw in the opposite direction is limited by a stop 32 which comes in engagement with the portion 40 29 of the stud or projection on the retaining-pawl 25, as shown in Fig. 3. If it be desired normally to maintain the levers in the upright position indicated in Figs. 1 and 2, the lever 8 may be made sufficiently 45 heavy to restore lever 7 to its upright position when released by the operator. Obviously, an independent counterweight, or its equivalent, a spring, would perform the same office.

The main or attaching plates of the supports 4 and 5 are here represented as in a plane perpendicular to the axis of the arbor 6, but either or both may be oblique thereto, or curved to fit the contour of the wall or body to which the device is to be applied, and this will be necessary or desirable where the structure is to be applied to curved end walls or vestibule walls of cars and the like. 55 The precise form of the several parts is not material, provided they embody the general principles of construction and mode of action above set forth, but the drawings indicate a form which possesses the desir-

able properties of compactness and strength, 65 and which permits the ready assembling of the parts.

From the foregoing description it will be seen that the structure possesses the following desirable characteristics: By providing 70 a central shaft and a drum loose thereon, the main shaft or arbor may be made of any desired length, extended through a wall or partition, and provided on each side thereof with an actuating lever. This is very desirable in many situations, notably in connection with car brakes. The winding drum is independent of the shaft or arbor and may be independently renewed, thus permitting drums of different length and diameter to be supplied without change in other parts of the device. It also permits the employment of cast metal for the drum and wrought metal for the shaft. Release of the drum is effected through movement of 80 the same lever which serves to effect rotation of the ratchet and drum, such movement being merely carried further when release is to be effected than when winding of the chain is to be performed. This avoids the 85 complication incident to independent releasing devices to be operated independently of the hand-lever, as has been proposed in some instances, and takes the release device from the floor or platform where it is sometimes placed; hence removes the liability of disengagement by persons passing the device. Release is effected by the actuating-lever acting upon the same pawl which normally serves as a retaining pawl, and this 90 is accomplished through merely moving the lever an abnormal distance. One ratchet-wheel serves for the engagement both of the actuating-pawl and the retaining and releasing pawl. The same abnormal movement of the actuating-lever which withdraws the retaining and releasing pawl causes the actuating-pawl to be withdrawn 95 from engagement with the ratchet. Withdrawal of the actuating-pawl in advance of 100 the retaining-pawl, and reengagement of the retaining-pawl in advance of the actuating-pawl, protects the operator against shock incident to premature release or backward throw of the actuating-lever. The 105 structure consists of few parts all of which are simple, strong and inexpensive, and the device is at once compact and efficient.

Having thus described our invention, what we claim is:

1. A ratchet-actuating mechanism comprising, in combination, a shaft; suitable supports in which said shaft is rotatably mounted; a hand-lever secured to said shaft; a pawl pivotally carried by said lever; a drum loosely encircling said shaft and provided with a ratchet wheel, the peripheral teeth of which lie in the path of said pawl,

and a locking pawl carried by the shaft support and normally engaging the teeth of the ratchet wheel to prevent backward rotation of the drum.

5. 2. A ratchet-actuating mechanism comprising, in combination, a shaft; suitable supports in which said shaft is rotatably mounted; a hand-lever secured to said shaft; a drum loosely encircling said shaft and 10 provided with a ratchet-wheel having peripheral teeth; a pawl carried by said lever and arranged to engage the teeth of the ratchet-wheel; and a second pawl carried by a fixed support normally engaging the 15 teeth of the ratchet-wheel, but arranged in the path of the hand lever and adapted to be disengaged from the ratchet by abnormal throw of the lever in non-winding direction.

3. A ratchet-actuating and release device 20 comprising, in combination, a shaft or arbor; suitable supports in which said shaft is mounted to oscillate; a hand-lever secured to said shaft and provided with a pawl-releasing cam; a drum loosely encircling and 25 supported by said shaft, and provided with a ratchet-wheel having peripheral teeth; an actuating-pawl carried by said lever, arranged to engage said ratchet-wheel, and having its free end beveled; and a retaining- 30 pawl carried by a fixed support, arranged also to engage the teeth of the ratchet-wheel, and provided with a lateral stud or projection in the path of the beveled end of said actuating-pawl and of the releasing- 35 cam of the actuating-lever, said parts being arranged substantially as described, whereby upon a normal oscillation of the lever the actuating-pawl imparts rotary movement to the ratchet-wheel and drum and the retaining-pawl holds the same against backward 40 rotation, and upon abnormal movement of said lever the actuating-pawl engages the stud and is lifted out of engagement with the ratchet teeth, and the releasing-cam 45 thereafter withdraws the retaining-pawl from engagement with the ratchet-wheel.

4. In a ratchet-actuating mechanism, the combination of a shaft or arbor; supports in which said shaft or arbor is mounted to 50 oscillate, one of said supports being provided with a lug spaced away from its shaft-supporting bearing; an actuating-lever secured to said shaft or arbor and provided with a flange or rib concentric with the axis 55 of the shaft, and extending into the space between the shaft-supporting bearing and the lug or projection carried thereby; a drum loosely encircling and supported by the shaft or arbor; a ratchet-wheel carried 60 by said drum; and a pawl pivotally mounted upon the actuating-lever and having a tooth or hook to engage the ratchet-wheel.

5. In a ratchet-actuating mechanism, the combination of a shaft or arbor; supports in

which said shaft or arbor is mounted to oscillate, one of said supports being provided with a lug spaced away from its shaft-supporting bearing; an actuating-lever secured to said shaft or arbor and provided with a flange or rib concentric with the axis of the 65 shaft; and extending into the space between the shaft-supporting bearing and the lug or projection carried thereby; a drum loosely encircling and supported by the shaft or arbor; a ratchet-wheel carried by said drum; an actuating-pawl pivotally mounted upon the actuating-lever and having a tooth or hook to engage the ratchet-wheel; and a retaining-pawl mounted upon a fixed support 70 and adapted also to engage the ratchet-wheel 75 to prevent backward rotation thereof.

6. A ratchet-actuating mechanism comprising a main support having a base provided with a bearing face and with a bracket spaced away from said bearing face; a 80 ratchet-wheel located in the space between said bearing face and said bracket; a supporting shaft or arbor passing through said ratchet-wheel and supporting bracket; a lever secured to said shaft or arbor; and a 85 pawl pivotally carried by said lever and arranged to engage said ratchet.

7. A ratchet-actuating mechanism comprising a main support having a base provided with a bearing face and with a bracket 90 spaced away from said bearing face, said bracket being in turn provided with a lug spaced away from its outer face; a ratchet-wheel located in the space between said bearing face and said bracket; a supporting 95 shaft or arbor passing through said ratchet-wheel and supporting bracket; a lever secured to said shaft or arbor, having its attaching head provided with a peripheral rib or flange to enter the space between the 100 bracket and the lug thereon; and a pawl pivotally carried by said lever and arranged to engage said ratchet.

8. In a ratchet-actuated drum mechanism of the character described, a winding drum 110 having a hub or boss provided with a bearing face to receive and support a link of a winding chain; a bolt carried by said hub and passing through said link; and a lug or projection formed upon said hub or boss, 115 and extending into the link on that side of the bolt toward which stress upon the chain tends to move the bolt, whereby said bolt is supported against the bending stress exerted through the chain, and the link is held 120 against lateral movement.

9. In a ratchet-actuating mechanism, the combination of a ratchet-wheel; a supporting shaft or arbor therefor; an actuating-lever carried by said shaft; an actuating-pawl carried by said lever and arranged normally to engage said ratchet-wheel, but to be withdrawn therefrom upon abnormal move- 125

ment of said lever; a retaining-pawl carried by a fixed support and likewise arranged normally to engage said ratchet-wheel, and provided with a stud upon which the actuating-pawl rides upward when said pawl is moved to abnormal position; and a cam carried by said lever and serving through engagement with the retaining-pawl to with-

draw the same from engagement with the ratchet-wheel, and through the movement of 10 said retaining-pawl to further lift or move outward the actuating-pawl.

In testimony whereof we have signed our names to this specification.

WALTER H. JANKE.
JOSEPH A. HALE.
